ALBERT PALMER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

ATTACHMENT FOR LOOMS.

Application filed January 4, 1928. Serial No. 244,515

This invention relates to improvements in devices for analyzing the picking motion of a loom and it is the general object of the invention to provide a means to be operated by the shuttle to determine when the latter passes a given point in its flight, preferably the selvage of the cloth.

In weaving one of the systems of threads is supplied by a shuttle which moves back and forth to lay shots of filling. The shuttle is propelled by so-called picking mechanism which usually involves some form of cam and cam lever operatively connected to a so-called picker stick which imparts motion to the shuttle by means of a leather or rawhide picker. The lay swings back and forth in the loom frame by means of connectors which extend from a crank shaft and the parts are so timed that the shuttle is in flight while the lay is in its rearward position, the harnesses separating the warp threads to define sheds at the same time so that the shuttle may pass between the warp threads to lay the filling. As ordinarily constructed the picking motion of the loom is rather harsh in its action and is found not to be entirely uniform in its operation so far as the time of flight of the shuttle is concerned. It is an important object of my present invention to provide a device to be applied to the lay and actuated by the shuttle to determine the time at which the shuttle passes any given fixed point.

It not infrequently happens that the width of a cloth to be woven on looms will vary so that at one time a loom is called upon to weave a rather wide cloth while at another time the same loom will be called upon to weave a narrower cloth. It is always desirable to have the sheds open as wide as possible when the shuttle enters them so that a minimum of resistance may be offered the flight of the shuttle. It will be seen that when a loom is weaving wide fabrics the shuttle will enter the shed earlier in the cycle of the pick than would be the case if the cloth were narrow. It is desirable of course to have a shuttle start its flight as soon as possible and the length of time required for the shuttle to pass through the shed is one thing determining the speed of the loom. In other words, if the shuttle can be started earlier in its flight it can be expected to arrive earlier

in the box on the opposite side of the loom, and therefore the speed of the loom can be increased. It is a further object of my invention to provide a device which will record the point in the cycle of the pick at which the shuttle enters the shed, use of the device making it possible to set the picking cam ahead somewhat on narrower fabrics, the amount by which the cam may be set forward being determined by the device set forth herein.

In a loom employing a plurality of shuttles such as a fancy box loom it may be desirable to confine the studies of the picking motion to one shuttle and it is accordingly a further object of my invention to provide means whereby a record may be made at the will of the operator so that the use of the device can be confined to one shuttle if desired.

With these and other objects in view which will appear as the description proceeds, my invention resides in the combination and arrangement of parts hereinafter described and set forth in the claims.

In the accompanying drawings wherein a convenient embodiment of my invention is shown,

Fig. 1 is a top plan view of the invention showing one part thereof supported by the breast beam and the other part moving with the lay,

Fig. 2 is a side elevation taken in the direction of arrow 2, Fig. 1 with certain parts in section, the lay being in its foremost position,

Fig. 3 is a vertical section on line 3-3 of Fig. 1,

Fig. 4 is a view similar to Fig. 2 but with the lay moved backwardly and the graph being described on the part fixed to the breast beam being partly completed, and

Fig. 5 represents one of the sheets having marked thereon the curve or graph produced by the device in conjunction with the shuttle.

In the drawings I have shown a loom frame 10 having a breast beam 11 and have also shown a lay 12 having a reed 13 and a hand rail 14. The lay and parts supported thereby move back and forth each pick of the loom by mechanism not shown but well understood. The shuttle 15 moves along the lay over the race plate 16 and has the rear side thereof normally in contact with reed 13.

The parts thus far described are of common construction and form no particular part of my present invention.

My improvements relate to means for determining the time when the shuttle S passes a given point along the lay and in carrying my invention into effect I divide the structure into two parts, namely, the mechanism which is relatively stationary and mounted on the breast beam and the moving part which is supported by the lay and cooperates with the shuttle. A stand 20 is secured to breast beam 11 by bolts 21 and has upstanding therefrom a pair of spaced walls 22 preferably perpendicular to the length of the lay and breast beam. A board 23 has projecting therefrom a pair of spaced guide rods 24 which pass through the walls 22, thereby guiding the board 23 and holding the same so that the face thereof shown in Fig. 2 will be substantially vertical. One of said rods has adjustably secured thereto a collar 25 positioned to engage one of the walls 22 to limit movement of the board while the other rod is surrounded by a comparatively light compression spring 26 interposed between one of the walls 22 and a pin 27 carried by the corresponding rod. The spring 26 acts normally to hold the board toward the adjacent wall 22 but by pressing on one of the rods 24 the board may be moved away from the walls until the collar 25 limits movement thereof.

The board 23 may be made of any convenient material such as wood and is adapted to receive a sheet of paper 28. Said paper may be held in position by thumb screws 29 passing into the board. I do not wish to be limited to the particular kind of paper employed.

The moving part of the device as previously stated is mounted on and moves back and forth with the lay and includes a bracket 30 secured as by bolts 31 to the hand rail 14. Said bracket has a vertical wall 32 which is substantially perpendicular to the hand rail and is provided with a slot 33 through which extends a stud 34 held in adjusted position in the slot by means of nut 35. A swinging arm 36 has a hub 37 through which the stud 34 extends to afford a pivotal mounting for the arm. The arm 36 carries a stop screw 36^a which is positioned to engage a portion of the bracket 30 to limit movement of lever 36 in a counter-clockwise direction as viewed in Fig. 2. Arm 36 is yieldingly held with the stop screw against the plate by means of a light tension spring 38 attached to the arm as at 39 and connected to the bracket 30 as at 40, said spring 38 permitting upward movement of the arm 36. The horizontal arm 41 of the lever 36 is provided with a hub 42 in which is adjustably secured a marking device 43 which may be a piece of crayon or may be any desired form of stylus.

The lever 36 has a depending arm 50 which has a rounded projection 51 normally pro-

jecting into the path of the shuttle S as shown in Fig. 2. The lever 36 is made light and may be stiffened by having a brace 52 extending between the arms 41 and 50.

In the normal operation of the loom to which my attachment has been applied the spring 26 will hold the paper 28 out of reach of the stylus or marking element 43 and as the lay moves back and forth said stylus and the lever will be moved correspondingly. When it is desired to make a graph showing the time at which the shuttle engages the rounded end 51 of the lever the operator will push the board toward the stylus to assume the position shown in Fig. 1, preferably at the time when the lay is in its extreme forward position. As the lay starts to move rearwardly the stylus will make a mark on the paper which will in effect be an arc described around the center of the lay. During the backward movement of the lay at a time when the lay is approximately midway between its forward and extreme rearward positions the picking motion not shown will be brought into action and the shuttle will be started in its flight across the lay. As the shuttle travels its advancing nose will ultimately engage the rounded end 51 and swing the lever 36 around the stud 34 against the action of the light tension spring 38. In doing so the marking element 43 will describe a path which will be other than an arc concentric with the axis of the lay. As the shuttle passes beyond the rounded end 51 the spring 38 will move the lever back to its normal position relatively to the hand rail and as the lay arrives at its rear-most position the stylus will again be found describing an arc concentric with the center of the lay. On the return movement of the lay a corresponding operation of the device will take place by the rocking of the lever 36 relatively to the hand rail but will take place at a different time in the pick inasmuch as the shuttle must pass through the shed before engaging end 51 of lever 36.

By referring to Fig. 5 the result of the operation of the device can be understood. I have shown a card 28 having thereon a mark or graph having an arcuate portion 60 which is substantially concentric with the center of the lay. This portion 60 of the graph corresponds to the rearward movements of the lay when the latter is forward of its mid position. By means of vertical dot and dash lines in Fig. 5 I have indicated the three principal positions the lay occupies when moving from its forward to its rearmost position. The line FC which marks the beginning of the left hand end of the portion 60 of the graph represents the so-called front center position of the lay when the latter is in its foremost position. The second dot and dash line marked TC represents the so-called top center which corresponds to the position occupied by the lay when the latter is approxi-

mate one-half the way between its foremost and its rearmost position. The third line BC represents the so-called back center or the extreme rearmost position which the 5 lay assumes.

It is usual practice to set the picking cam of the loom so that it will begin to move the picking motion and shuttle when the lay is on so-called top center or midway between its 10 extreme forward and rearward position with the lay moving rearwardly. It takes a small fraction of a second for the lost motion of the various connections between the cam and the shuttle to be taken up, after which the shuttle 15 will start to move out of the box. By having the rounded end 51 located approximately over the selvage of the cloth it is possible to determine with considerable accuracy what the position of the lay is at the time the shuttle 20 enters the sheds defined by the warp threads. As shown in the graph illustrated in Fig. 5 the shuttle enters the shed when the lay is approximately one-fourth of the distance between top center and back center and the 25 graph shows a corresponding quick upward trend 61. After the shuttle has passed the device spring 38 will return the marking element 43 to its normal position and the graph will return by means of line 62 to a continuation 30 of the beginning of the graph shown at 60. The distance between the ascending and descending lines 61 and 62, respectively, will depend somewhat upon the length of the shuttle, the sharpness of the blow struck the 35 end 51 by the shuttle, and the strength of the spring 38. The line 62 ordinarily is of little consequence, the important part of the graph being the point where the curve ceases to be concentric with the center of the lay and 40 moves upwardly along the line 61.

I have shown herein but one of the devices and have confined the explanation of the same so far as the graph is concerned to the flight of the shuttle in but one direction, but 45 it is to be understood that two devices may be used if desired, one at each side of the loom, and that the marking element 43 may be utilized to register the point in the cycle of the loom when the shuttle emerges from the sheds 50 as well as the point where it enters the sheds.

Tests made with the device set forth herein have enabled me to alter the picking motion of a loom to which the device has been applied so as to ease the action of the shuttle and to improve picking conditions. By the use of my present device the weaver can tell by measuring the point at which the shuttle engages the recording lever 36 what the proper relation should be between the picking motion and the harness motions of the loom. It is undesirable of course to have the harnesses open any appreciable length of time before the shuttle can enter the shed as this represents a waste of time. It is likewise undesirable to have the shuttle enter the sheds 55

before the harnesses are sufficiently open to permit an easy passage of the shuttle, otherwise the power of the pick must be increased beyond a desirable point merely to overcome friction between the warp threads and the 70 shuttle.

From the foregoing it will be seen that I have provided a very simple device for determining the time in the cycle of the pick of a loom at which the shuttle passes any selected 75 point and that by the use of the device the weaver may know by simple calculation from the chart or graph secured whether the picking motion and harness motions are properly related so as to provide best weaving conditions. 80

Having thus described my invention it will be seen that changes and modifications may be made therein by those skilled in the art without departing from the spirit and scope 85 of the invention and I do not wish to be limited to the details herein disclosed, but what I claim is:

1. A device of the class described for a loom having a relatively fixed breast beam and a lay moving toward and from the breast beam and a shuttle to move along the lay, a pair of cooperating indicating elements one of which is supported by the breast beam and the other of which moves with the lay, and 90 means actuated by the shuttle to cause relative movement between said members additional to that caused by the lay as the latter moves relatively to the breast beam. 95

2. A device of the class described for a loom having a relatively fixed breast beam and a lay moving toward and from the breast beam and a shuttle to move along the lay, means supported by the breast beam to receive a recording mark, a marking element 100 supported by and movable relatively to the lay to have engagement with the means on the breast beam, and means actuated by the shuttle as the latter is in flight to cause relative movement between the means and the marking element in addition to that imparted thereto by the lay as the latter moves relatively to the breast beam. 105

3. A device of the class described for a loom having a relatively fixed breast beam and a lay moving toward and from the breast beam and a shuttle to move along the lay, a pair of cooperating recording devices one of which is supported by the breast beam and the other of which moves with the lay, the device moving with the lay being relatively movable with respect to the latter and being movable by the shuttle while the latter is in flight to impart to said device supported by the lay a movement in addition to that caused by the lay as the latter moves relatively to the breast beam. 115 120 125

4. A device of the class described for a loom having a relatively fixed breast beam and a lay moving toward and from the breast 130

beam and a shuttle to move along the lay, a relatively fixed surface to have a graph marked thereon, a marking element supported by the lay to have engagement with the surface, said element capable of receiving two kinds of motion, one motion being imparted thereto by the lay alone as the latter moves relatively to the breast beam and the other motion being imparted thereto by the shuttle and lay combined as the lay continues to move relatively to the breast beam.

5. A device of the class described for a loom having a relatively fixed breast beam and a lay moving toward and from the breast beam and a shuttle to move along the lay, means supported by the breast beam presenting a surface to receive a mark, a lever supported by and pivotally mounted with respect to the lay, a marking element carried by the lever, and yielding means to hold said lever in normal position, said lever being engaged by the shuttle while the latter is in flight to move the lever against the action of the yielding means, whereby the marking element will produce a mark on the first named means corresponding to the time said lever and shuttle engage each other.

6. A device of the class described for a loom having a relatively fixed breast beam and a lay moving toward and from the breast beam and a shuttle to move along the lay, a recording member supported by the breast beam and movable from non-recording to recording position, and means supported by the lay and deriving movement from the shuttle when the latter is in flight to make a record upon said means to indicate the time in the cycle of the loom when the shuttle engages the device. 36 35

7. A device of the class described for a loom having a relatively fixed breast beam and a lay moving toward and from the breast beam and a shuttle to move along the lay, a recording member supported by the breast beam, and means supported by the lay and deriving movement from the shuttle when the latter is in flight to make a record upon said means to indicate the time in the cycle of the loom when the shuttle engages the device. 40 45 50

In testimony whereof I have hereunto affixed my signature.

ALBERT PALMER.
